LOOSE LEAF RECORD BOOK

Ernest C. Hazel and Ernest Hazel, Jr., Atchison,
Kans.

Application October 10, 1932. Serial No. 636,994

9 Claims. (Cl. 129—23)

This invention relates to loose leaf binders, and particularly that type known in the art as public record books, wherein is incorporated a series of sheet impaling posts releasably secured in position by hingedly mounted binding members having locking mechanism associated therewith that is constructed in a unique and novel manner to present a compact, durable, strong and automatically latching part which renders the binder 10 exceedingly desirable.

Another aim of the instant invention is the contemplation of a loose leaf binder having hingedly interconnected back and covers, the pin of said hinge also supporting a binding member for movement to and from a place in engagement with the posts and against the sheets of the filler, said back of the binder carrying guide stops for the purpose of engaging the bound edges of the sheets, whereby to maintain all of said parts in a place where 20 movement of the binding members to proper association with the posts is insured when said binding members are swung about the axial center of the hinge pin or when the cover of the binder is closed.

One of the salient objects of this invention is to provide unique locking structure to releasably and automatically engage the posts of a loose leaf binder without manual manipulation excepting when it is desired to release the locking members 30 from their grip on the posts.

More specifically, the invention contemplates the use within a chambered binding member, of a pair of relatively movable locking bars, between which is disposed resilient means for maintaining 35 the same in a predetermined position, as well as means for insuring that the said locking members are moved simultaneously when force is exerted upon either, all of the aforesaid parts of the locking mechanism being housed within the 40 binding member and disposed in the same plane.

The above enumerated objects, as well as many specific structural details forming a part of this invention, will be made clear during the course of the following specification, referring to the 45 accompanying drawing, wherein:

Figure 1 is an irregular, fragmentary, sectional view through a portion of a loose leaf binder made in accordance with the present invention.

Fig. 2 is a fragmentary, top plan view of parts 50 illustrated in Fig. 1.

Fig. 3 is a longitudinal, sectional view through one of the chambered binding members of the binder, showing the locking mechanism which is housed therein.

Fig. 4 is a fragmentary, detailed, sectional view 55

through a portion of the binder, taken on line IV—IV of Fig. 1.

Fig. 5 is a fragmentary, sectional view showing the relation of post and locking bars.

Fig. 6 is an enlarged detail view taken on line 60 VI—VI of Fig. 3, and,

Fig. 7 is a fragmentary, perspective view of one end of the binder posts.

A binder embodying the improvements contemplated by this invention is composed essentially of a back 10 and covers 12 that are hingedly associated with said back 10 and, in this instance, the hinge connection is made in a special manner, as illustrated in Fig. 1. Offset plate 14 is riveted or otherwise secured to each cover 12. A portion 65 of plate 14 lies along the inner face of associated cover 12, while another portion of the plate lies in substantially the same plane as the outer face of cover 12. The offset thus created is sufficient to accommodate the hereinafter described binding members and allows the placement of filler 70 sheets 16, as shown.

One edge of plate 14 is formed to present hinge barrels 18, through which is passed a rod 20 which acts as a pivotal member for all of the hingedly connected parts of the binder. To complete the hinge connection between back 10 and covers 12, there is provided a back plate 22 which is riveted as at 24 directly to the inner side of back 10. One edge of this plate 22 has hinge barrels 26 80 formed thereon, through which passes rod 20. This particular type of construction permits the use of standard parts for making binders of various capacities.

In each binder there are two plates 22 and 85 their distance apart is governed by the width of back 10. This manner of forming the binder has been found advantageous and the expedient does not rob the structure of rigidity or strength.

At each side of back 10 there is a hingedly mounted chambered binding member 28 which has ears 30 formed thereon for the reception of hinge rod 20. These ears extend outwardly from binding member 28, as illustrated in Fig. 1, and when the parts are assembled, covers, back and

binding member, 12, 10 and 28, all pivot about the axis of rod 20. A number of posts 32, which may be either straight or arcuate, are associated with binding members 28, and when the same are in the operative position supporting sheets 16, these posts are releasably engaged at each end thereof by structure carried by chambered binding members 28.

The binding edge 34 of filler sheets 16 lies in 105 a plane parallel to posts 32, and it is desirable 110

to stop the movement of back 10 toward filler sheets 16 at a point where binding members 28 may be swung into locking engagement with the posts. To accomplish this result, guide stops in 5 the form of ribs 36 are formed integrally with back 10 and are disposed transversely thereof at spaced apart points throughout its length. These ribs 36 are desirably located immediately opposite each post 32, as shown in Fig. 4.

10 When the binder is being closed back 10 is moved to a point where rib 36 and the binding edge 34 of sheets 16 engage, at which time the uppermost cover 12 may be thrown to the closed position without danger of binding members 15 and posts 28 and 32 not coming into proper engagement. These ribs 36 are created in precisely the same manner as the well known hubs are formed on the outer side of binder backs 10 and may be built up of binder's board or similar material.

15 The posts used in a binder embodying this invention are made in a special fashion, as shown in Figs. 1, 5 and 7. Each post is provided with an inwardly projecting notch 38 formed in each 20 edge near the ends of posts 32. A head is formed above these notches 38 and constitutes a number of converging, inclined faces 40 and 42, all of which meet on a single central line or edge. Apertures 44 are formed through one wall of 25 chambered binding members 28 to receive posts 32 and an emboss 46 is pressed from the opposite wall of member 28 in opposed relation to each aperture 44. The internal contour of these embosses 46 is precisely the same as the contour 30 of the head formed on said posts. The angles of inclination are the same as inclined faces 40 and 42, and when the post 32 is seated, as shown in Figs. 1 and 5, lateral movement is precluded and 35 rigidity is imparted thereto.

40 The bringing together of faces 40 and 42 so that they meet upon an edge extending across post 32 likewise requires that the post be centered at all times, thus to eliminate any possible binding upon the punchings of sheet 16 and also 45 to eliminate improper action on the behalf of the hereinafter described locking bars housed within members 28.

45 Unique locking structure forms an important part of this invention and reference to Fig. 3 50 readily indicates that the same comprises a pair of locking bars 48 and 50 that are positioned in the same plane and disposed in edge-to-edge relation within member 28. The abutting edges of bars 48 and 50 are specially formed to create 55 shoulders 52 and 54 respectively, between which is positioned a spring 56. This spring exerts its tension longitudinally upon bars 48 and 50, each bar being forced in a direction opposite to the other. Shoulders 52 and 54 are in spaced apart, 60 overlapping relation, and spring 56 is positioned therebetween in the same plane with bars 48 and 50.

To insure simultaneously longitudinal movement, each bar 48 and 50 has a rack 58 and 60 respectively formed thereon. These racks are in 65 facing relation and are in mesh with a pinion 62 which likewise lies in the same plane as bars 48 and 50. Pinion 62 is supported for free rotation by pintle 64, that is in turn carried by binding member 28. Thus pinion 62 will rotate but 70 cannot move longitudinally with either of the locking bars.

75 Post receiving openings 66 are created between opposed, tapered tongues 68 and 70, formed on bars 48 and 50 respectively. These tongues are

normally held a distance apart that is slightly less than the width of post 32 which is to enter opening 66, and are also directly adjacent each aperture 44 so that when post 32 is projected into the chamber formed by binding member 28, inclined faces 40 will move against the underside of tongues 68 and 70 to force them apart against the action of spring 56. These tongues immediately jump back into engagement with notches 38 and post 32 is thereby held in a locked position.

80 Locking bar 50 projects beyond the end of member 28 and has formed thereon a finger grip 72 which may be grasped when it is desired to move apart tongues 68 and 70 to release posts 32 from engagement by the locking structure. Such longitudinal movement as is manually imparted to bar 50 is transmitted to bar 48 through 85 rack and pinion arrangement illustrated in Fig. 3 so that all of the posts 32 of the binder may be released simultaneously. Obviously, notches 38 are in the same plane as the remaining above-mentioned parts of the locking structure when the same are in the locked position, all of which is an advantage not only from the standpoint of compactness, but from the point of creating an automatic latch which works in the above-mentioned manner without the use of a large number of complicated parts.

90 Structure such as hereinbefore set forth combines to produce a record book that is exceptionally desirable. When it is no longer necessary to place and remove sheets to and from the binder respectively, locking bars may be secured against 95 relative movement by depressing tongue 74 into opening 76. Tongue 74 is simply formed in the upper wall of binding member 28 by slitting three sides thereof, as shown in Fig. 2, and when a permanent lock is necessary, tongue 74 is merely driven into opening 76 which is formed through 100 one of the locking bars housed within binding member 28.

105 The operation of a binder embodying the features of this invention has been made clear during the course of the detailed specification, and while definite forms for the parts have been shown and described, it is understood that enjoyment of the invention is to be limited only by the spirit thereof and the scope of the appended claims.

110 Having thus described the invention, what is claimed as new and desired to be secured by Letters Patent is:

115 1. In a binder, the combination with a back, covers, binding members, means for hingedly interconnecting the back, a cover and a binding member for movement about a common axis, and sheet impaling posts, of guides formed by said back to limit the movement of said back toward said posts; and oppositely movable, spring actuated, locking bars carried by said binding members for releasably gripping said posts, said locking bars being disposed in the same plane in edge-to-edge relation.

120 2. In a loose leaf binder, a back; covers; hinges interconnecting said back and covers respectively; a chambered, binding member, having apertures formed through the side thereof, swingably carried by each hinge respectively for movement 125 about the axis of the latter; sheet impaling posts each having notches formed adjacent the ends thereof; a pair of post engaging bars within each binding member; a spring exerting yielding pressure upon said bars longitudinally thereof; and 130

- a rack and pinion connection between said bars to insure simultaneous movement, said bars, spring and rack and pinion all being in the same plane with said bars in edge-to-edge relation.
- 5 3. In a loose leaf binder, a back; covers, hinges interconnecting said back and covers respectively; a chambered binding member, having apertures formed through the side thereof, swingable carried by each hinge respectively for movement about the axis of the latter; sheet impaling posts each having notches formed adjacent the ends thereof; a pair of post engaging bars within each binding member; a spring interposed between said bars and exerting yielding pressure thereupon in opposite directions; a rack and pinion connection between said bars to insure simultaneous movement thereof; and an emboss formed in each binding member opposite each aperture formed thereon, said bars, spring and rack and pinion all being in the same plane, said posts projecting into said embosses of the binding members, through the respective apertures and intersecting the plane of said locking members and said associated parts.
- 25 4. In a loose leaf binder of the character described, chambered binding members each having an aperture formed through one wall thereof; an emboss formed by the opposite wall in opposed relation to each aperture; and a post traversing said binding members through each aperture respectively and into the respective emboss, said post having opposed notches formed inwardly from each edge respectively thereof adjacent the ends, and converging, inclined faces all meeting at a common edge at each end of the post, each emboss having interior faces inclined similarly to the inclined faces of said post, said faces being in engagement to center said post in the post receiving apertures and to preclude relative lateral movement between said post and binding members.
5. In a loose leaf binder of the character described, a chambered binding member, having apertures formed through one wall thereof; posts each having opposed notches formed in opposite edges thereof; an inclined face extending upwardly and inwardly from each notch respectively; means for swingably mounting said binding member for movement to and from a position where the posts project into the chamber of said member through said apertures; and a pair of spring actuated, longitudinally movable locking bars housed by said binding member, each movable in an opposite direction by engagement with the respective inclined faces whereby to guide the same into said notches, said notches and both bars all being in the same plane when interengaged.
- 60 6. In a loose leaf binder of the character described, a swingable chambered binding member, having an aperture formed through one wall thereof; a notched post positioned for projection into the chamber through the said aperture; and releasable structure within the chamber of the binding member for engaging said post when the binding member is swung comprising oppositely movable locking bars in edge-to-edge, relation, a shoulder formed on each bar, and a spring bear-
- ing against said shoulders to urge said bars into the notches of said post, said bars, notches and spring all being disposed in the same plane within the said chamber of the binding member.
7. In a loose leaf binder of the character described, a swingable chambered binding member, having an aperture formed through one wall thereof; a notched post positioned for projection into the chamber through the said aperture; and releasable structure within the chamber of the binding member for engaging said post when the binding member is swung comprising a pair of oppositely movable locking bars having portions of their longitudinal edges in abutting relation and formed to provide spaced apart shoulders, a spring between said shoulders and exerting pressure against said bars, longitudinally thereof and in opposite directions to each other, and opposed, tapered, notch-engaging tongues formed by the said bars, said bars, spring, tongues and notches all being disposed in the same plane within the said chamber of the binding member.
8. In a loose leaf binder of the character described, a swingable chambered binding member, having an aperture formed through one wall thereof; a notched post positioned for projection into the chamber through the said aperture; and releasable structure within the chamber of the binding member for engaging said post when the binding member is swung comprising a pair of oppositely movable locking bars having spaced shoulders formed along their abutting longitudinal edges, a spring between two of said shoulders to urge the bars longitudinally in opposite directions to each other, facing racks formed on said bars, and a rotatable pinion in mesh with both of said racks, a pintle carried by said binding member and supporting said pinion for free rotation, said pinion, bars, and spring all being disposed in the same plane within the said chamber of the binding member.
9. In a loose leaf binder of the character described, a swingable chambered binding member, having an aperture formed through one wall thereof; a notched post positioned for projection into the chamber through the said aperture; and releasable structure within the chamber of the binding member for engaging said post when the binding member is swung comprising a pair of oppositely movable locking bars, shoulders formed on said bars, a spring between said shoulders to urge the bars longitudinally in opposite directions to each other, facing racks formed by the said bars, a pinion in mesh with both of said racks, a pintle carried by said binding member to support said pinion for free rotation whereby to cause the said bars to move simultaneously in opposite directions when one of said bars is moved, and facing, tapered tongues integral with the bars to engage the notches of the post, said bars, shoulders, spring, pinion, racks and tongues all being disposed in the same plane within the said chamber of the binding member.
